UNITED STATES PATENT OFFICE.

LEONARD F. FULLER, OF SAN FRANCISCO, CALIFORNIA, ASSIGNOR TO FEDERAL TELEGRAPH COMPANY, OF SAN FRANCISCO, CALIFORNIA, A CORPORATION OF CALIFORNIA.

RADIOTELEGRAPHY.

1,300,157.

Specification of Letters Patent.

Patented Apr. 8, 1919.

Application filed March 27, 1916. Serial No. 86,935.

To all whom it may concern:

Be it known that I, LEONARD F. FULLER, a citizen of the United States, and a resident of the city and county of San Francisco, 5 State of California, have invented certain new and useful Improvements in Radiotelegraphy, of which the following is a specification.

The invention relates to transmission systems of radiotelegraphy and particularly to a means of signaling.

An object of the invention is to provide a signaling system for high powered transmission stations.

15 The invention possesses other advantageous features, which, with the foregoing, will be set forth at length in the following description, where I shall outline in full that form of the invention which I have selected for illustration in the drawing accompanying and forming part of the present specification. In said drawing I have shown only one specific form of my invention, but it is understood that I do not limit myself 25 to such form.

In the drawing I have shown diagrammatically one form of transmission system of my invention. The system includes a suitable source of oscillations, preferably 30 continuous oscillations, such as the arc 2 which is inclosed in a hydrogen atmosphere. Current is furnished to the arc by a direct current generator 3. One side of the arc is grounded by the conductor 4 and the other 35 side is connected to the radiating conductor or antenna 5, through the conductor 6 and the variable inductance 7. Signaling has heretofore frequently been effected by varying the wave length of the radiated wave, 40 by short-circuiting a portion of the inductance, but in high powered stations the current in the short circuit is large, making signaling difficult.

In accordance with the present invention, 45 I provide a circuit containing an inductance 8, a capacity 9 and a variable resistance 12, which is shunted around the arc 2. The resistance 12 comprises an arc, the spacing of the electrodes of which is preferably such 50 that normally a very small amount of current will pass across the arc, making the shunt circuit practically an open circuit and confining the oscillations to the antenna cir-

cuit. The resistance of the arc gap is preferably such that the current will spit across 55 the gap spasmodically, but will not flow continuously. Means are provided for impressing an additional voltage on the arc 12, to reduce the resistance thereof and form a path for the current from the arc 2. Shunted around the arc 12 is a circuit containing a source of E. M. F., such as a direct current generator 13 and a signaling key 14 which is preferably provided with a magnetic blow-out or other arc extinguishing means. The 60 generator 13 may produce a current of 500 volts, which when impressed on the arc 12 causes the gap to be bridged, so that the current from the generator 13 forms a bridge over which the current from the arc 2 passes. 65 Closing the key 14 will therefore operate to close the shunt circuit around the arc 2 thereby causing the shunt circuit to become the oscillatory circuit and opening the key will cause the shunt circuit to be opened and 70 the oscillations to be confined to the antenna circuit. The arc 12 is preferably provided with a magnetic blowout which extinguishes the arc 12 when the key is opened.

I claim:

1. In a radiotelegraphy transmission system, an arc, a radiating conductor connected to one side of said arc, a grounded conductor connected to the other side of said arc, a circuit containing capacity, inductance and 85 a gap shunted on said arc, a source of current connected to opposite sides of said gap and a key for controlling the flow of said current.

2. An arc system for radio signaling comprising an antenna circuit and an absorption circuit both in parallel and shunted across the arc and means for varying the vibration period of the absorption circuit comprising a gap in said circuit and means for varying 90 the electromotive force impressed on said gap, so that the gap may be opened or closed to the flow of radio-frequency current from the arc.

In testimony whereof, I have hereunto set 100 my hand at San Francisco, California, this 21st day of March 1916.

LEONARD F. FULLER.

In presence of—
H. G. PROST.
